UNITED STATES PATENT OFFICE.

ARTHUR HAROLD WILKS, OF OLTON, NEAR BIRMINGHAM, AND PERCY HAROLD HARTSHORNE, OF BIRMINGHAM, ENGLAND.

INTERNAL-COMBUSTION ENGINE.

1,313,569.

Specification of Letters Patent. Patented Aug. 19, 1919.

Application filed September 28, 1917. Serial No. 193,706.

To all whom it may concern:

Be it known that we, ARTHUR HAROLD WILKS, of "Lansdown," Warwick Road, Olton, near Birmingham, England, and 5 PERCY HAROLD HARTSHORNE, of 22 Claremont road, Smethwick, Birmingham, England, and now in the British royal naval air service, both subjects of the King of Great Britain, have invented certain new and useful 10 Improvements in Internal-Combustion Engines, of which the following is a specification.

This invention has reference to internal-combustion engines for aeroplanes and the 15 like, and consists in an improved engine of the rotary cylinder type, which operates on the two-stroke or two-cycle principle.

The general arrangement of the said engine is shown in the accompanying drawings, in which

Figure 1 is a half longitudinal section, and half side elevation; the sectional part illustrating one of the cylinders, with its piston and its system of inlet, transfer, exhaust and firing ports.

Fig. 2 is a half end elevation and a half transverse section, while

Fig. 3 is an enlarged sectional view of one of the cylinders showing the positions of 30 the pistons and valve sleeve pertaining to that cylinder when the pistons are at the outer ends of the strokes and the ports in the reciprocating and non-reciprocating parts which are then fully open.

Fig. 4 is a sectional view of one of the cylinders showing the positions of the various ports when the pistons are at the inner ends of their strokes.

The same letters of reference indicate corresponding parts in the several figures.

An engine constructed in accordance with the said invention comprises a rotary cylinder member or unit which is connected to, and rotates with, the engine shaft, and a 45 stationary member or casing which is bolted to a fixed frame or other support and carries the carburetors and is furnished internally with a system of fixed cams or inclined planes against which the outer ends of the 50 reciprocating piston-rods have a constant bearing; the said cams functioning to transform the outward or working thrust of the pistons into a rotary motion for driving the cylinder unit and shaft, and to impart the 55 inward or return stroke to the said pistons

for inducing and compressing the explosive charges in the cylinders.

In the engine shown in the drawings, the rotary cylinder unit A embodies a series of twelve cylinders a^2 each provided with two 60 pistons, while the stationary member B consists of a cylindrical aluminum casing which is built-up of bolted-together sections (preferably two end sections b^2 and a middle section b^3) which are provided externally with 65 arms or webs whereby the same may be bolted to a fixed frame or other support, while the two end sections are furnished centrally with journal and thrust bearings for the rotary engine-shaft e that is directed 70 horizontally through the said casing. Each of the said end section supports has on its inner side a stationary thrust-transforming cam or track C, which is more fully described hereafter while the middle section 75 b^3 is provided externally with two carbureter unions, which are arranged diametrically opposite to one another, and to whose intakes b^4 , suitable carbureters are connected.

The rotary unit A consists of a body member a^2 which is also preferably an aluminum casting, and carries the group or block of twelve cylinders a^2 , arranged in an annular series, with their axes parallel with the axis 80 of the engine shaft. The cylinders consist of open-ended steel tubes or liners, which are shrunk in the body casting, and whose open ends are closed by gland-plates or castings a^3 which are bolted to the opposite ends 85 of the said body casting, and also to flanges e^1 at the inner ends of the sections e^2 of the shaft e ; each of the said gland plates being formed with a series of glands a^4 whose axes register with the axes of the cylinder-tubes 90 and wherethrough the reciprocating piston rods f of the engine work. These gland plates close the outer ends of the cylinder-tubes and form transfer compression chambers or pump-chambers f^1 outward of each 95 piston.

Each cylinder of the group is provided with a pair of pistons f^2, f^3 rigidly attached respectively to the inner ends of the two piston rods pertaining to that cylinder, and 100 one piston f^2 of each pair is made to function as a sleeve valve for opening and closing the inlet, transfer and exhaust ports that are formed in the walls of the cylinder-tubes. For this purpose, the said piston f^2 110

(i. e., the valve-controlling piston) carries a tubular extension or sleeve f^4 that reciprocates within the cylinder and sockets over the other piston f^3 which reciprocates with 5 in the said sleeve; the valve-controlling piston being provided with a piston-ring or rings f^5 fitting the interior of the cylinder, and the second or short piston f^3 having a piston-ring or rings f^6 fitting the interior 10 of the reciprocating sleeve. The sleeve itself may also be furnished with an additional piston-ring or rings f^7 fitting the cylinder.

At a suitable distance from the ends of each cylinder tube there are formed a pair 15 of induction ports g^2 and g^3 both communicating with a common induction passage g^4 which is cast in the walls of the cylinder body, and whose intake g^5 is adapted to periodically register with induction passages 20 in the walls of the stationary members that communicate with the carburetors by way of intakes b^4 ; both the cylinder induction ports g^2 and g^3 being controlled or opened and closed by the reciprocating sleeve valve or 25 piston extension f^4 , which is also formed with a port at f^8 which registers with the induction port g^3 only when the pistons at the inner ends of their strokes, or on their "in-centers", as shown in Fig. 4. Both 30 ports g^2 , g^3 are then uncovered or open for admitting explosive charges into the pump-chambers f^1 , as the sleeve-port f^8 registers with the right-hand induction port g^3 , while the left-hand induction port g^2 leads straight 35 into the pump-chamber f^1 outward of the left-hand piston.

Two transfer ports i^2 and i^3 are also formed in the outward end of every cylinder tube; each pair of said ports being in connection with one another by a transfer 40 passage i^4 cast in the cylinder body, and they (the ports i^2 and i^3) are respectively controlled by suitable ports j^2 and j^3 in valve sleeve in such a manner as will admit of 45 transfer of explosive mixture from the pump-chamber f^1 into the combustion-chamber h between the pistons during outward strokes of the latter.

An exhaust port k for each cylinder is 50 formed in about the middle of each cylinder tube; this being in constant communication with an exhaust passage k^2 cast in the cylinder body, and controlled by a port k^3 that is formed in the valve sleeve and is timed to 55 register with the cylinder exhaust port when the pistons are at the outer ends of the strokes (see Figs. 1 and 3). The sleeve also has a suitably-disposed firing port (not shown in the drawings) which, after compression of the charge in the combustion-chamber by the in-strokes of the piston, 60 registers with a firing port m^2 in the cylinder and with a sparking plug chamber m^3 in the cylinder body; thus providing for the 65 ignition of the compressed charge at the ap-

propriate time. The chambers b^3 are fitted with sparking plugs which are wired to a rotary distributor carried on the engine shaft.

The whole of the exhaust passages k^2 in 70 the body of the rotary cylinder unit communicate with an exhaust manifold k^4 which may be cast in the cylinder body and is connected up with an exhaust pipe k^5 that is directed outward through a hollow section 75 of the main shaft; an asbestos or like jacket being pressed into the said hollow part of the shaft where it passes through the bearing in order to protect the latter from the heat.

The gland plates at the right-hand side of 80 the cylinder unit are formed, on their inner sides, with annular clearances a^5 that register with the cylinder tube ends into which the right-hand ends of the corresponding valve sleeves extend during the inward 85 strokes of the pistons f^2 .

The engine is air-cooled; the exterior walls of the cylinder body being cast with suitably arranged cooling gills or fins, while openings are formed in the end gland plates 90 of the rotary unit to provide for the circulation of air through the inside of the said body.

Each of the reciprocating rods f of the cylinders is forked at its outer end n and 95 the fork is fitted with a roller or bushing n^2 mounted on ball or other anti-friction bearings interposed between the said roller and a pin n^3 that is located across the branches or cheeks of the said fork. These 100 forks n saddle or seat upon, and travel around, the inclined cam-tracks or planes C , which, as already mentioned, are fixed inside the two end sections b^2 of the stationary engine-casing.

These cam-tracks are in the form of zig-zag rings which are mounted concentrically 105 to the engine-shaft, and are of the same diameter as that of the circle which contains the axes of the annular series of cylinder tubes; each track comprising a succession of four inclined planes arranged in the form of two complete V-like cams, with one side of each V sloping inwardly from the end 110 of the fixed casing toward the rotary unit, and the other side sloping in the reverse direction, i. e., from the rotary unit toward the casing ends.

The outer ends of the two piston rods of each cylinder are slidably connected or 120 coupled respectively with the cam-rings at the opposite ends of the casing B by reason of the fact that their forks n saddle over the corresponding rings, and the arrangement is such that, as each piston rod makes 125 its outward or working stroke under the impulse derived from the explosion of a cylinder charge, it travels along an outwardly sloping or retiring plane of its cam ring which re-acts, through the piston rod, 130

upon the rotatable cylinder unit A and thus transforms the longitudinal piston thrust into a rotary motion for driving around the said cylinder unit A and shaft e, whereas 5 when each piston rod has completed its driving stroke down the outwardly-sloping plane and comes into engagement with the succeeding inwardly-sloping or advancing plane, it is forced inward by the action of 10 the said plane for the induction and compression stroke.

Thus, as the right-hand pistons of all the cylinders are in engagement with the right-hand fixed cam-ring and all the left-hand pistons are in engagement with the left-hand cam-ring, and as there are two inward planes alternating with two outward planes in each ring, it follows that, in the twelve-cylinder rotary unit now being described, the two 15 pistons of each cylinder make two working or impulse strokes and two induction and compression strokes during each complete rotation of the said unit.

All the piston rods are preferably made 20 hollow for lightness and so also that they may be used to convey oil (by passages o⁵) to the piston walls, and also to the ball-bearings of the cam-engaging forks through holes o that are drilled in the said rods and 25 communicate with supply leads or passages o² formed in the gland plates; the distribution of oil to the cylinder walls and bearings in the rotary unit being assisted by the centrifugal action. Suitable pipes or other 30 connections such as o³, o⁴ are also provided for supplying oil to the main shaft bearings, and preferably all the passages, pipes and leads of the system are suitably connected with a central oil reservoir connected to a 35 40 suitably arranged oil-pump, while partition plates o⁶ fitting the cylinders may be arranged on the inner ends of the hollow piston rods, outward of the piston-oiling leads o⁵ from the said hollow rods, to prevent the 45 escape of charges of gas from the transfer compression chambers during the transfer strokes.

Oil-retaining covers p may be fixed inside 50 the ends of the stationary casing to extend over the end gland-plates of the rotary unit and so inclose the cam-rings and piston rod ends working thereon; these covers being provided with suitable oil-drainage pipes p¹ connected with the oil-circulating system. 55 Packing rings q may also be inserted between the outside of the middle part of the rotary cylinder body and the interior of the stationary casing, to prevent air-leaks into the induction passages that is cast in this 60 part of the said cylinder body.

As already stated, the formation and disposition of the cam rings insures that each cylinder will give a double impulse twice in each revolution of the rotary unit; all twelve 65 cylinders firing twice during each revolution

and the diametrically opposed cylinders firing simultaneously. The firing angle is 30° so that six cylinders are doing work at the same time; two being two-thirds through the working stroke, two one-third through, 70 and two commencing; each of these pairs being diametrically opposed. Thus the driving effort is practically continuous while the general arrangement of the parts makes for perfect balance and reduces vibration to a 75 minimum.

It may be added that, when the improved engine is running, as each piston approaches its "in-center" the in-chamber f¹ in the outer end of the cylinder, and that, at a certain 80 point before this in-center is reached, the sleeve valve opens communication between the cylinder induction-ports g² and the chambers f¹ to enable new charges to pass into the outer ends of the cylinder. On 85 further rotation, and as the pistons move outward, these charges will pass through the transfer ports and passages into the combustion chambers between the backs of the pistons, while as the continuation of the rotation takes the pistons back to in-center again, the transferred charges are compressed and fired to give the impulse stroke. The valve-sleeve exhaust ports are opened or 90 brought into register with the exhaust passages of the cylinder body as the pistons approach their outer center; the cycle of operations providing for each pair of pistons obtaining an impulse at each in-center and transferring a charge at each outer center, 100 while as the pistons of two diametrically opposed cylinders reach in-center together, two explosions occur simultaneously.

Having now described our invention, what we claim and desire to secure by Letters 105 Patent is:—

1. An internal combustion engine operating on the two-stroke principle comprising a rotary member, an annular series of parallel cylinders embodied in the said member, 110 two reciprocating pistons arranged in each of said cylinders, a valve sleeve connected to one of said pistons, induction, transfer and exhaust ports adapted to be controlled by said sleeve, cam tracks adapted to accommodate the action of the piston in effecting the rotation of the rotary member comprising oppositely inclined contact edges or surfaces disposed outward of the opposite ends of the series of cylinders and bearing devices 115 120 on the rods of the pistons for engaging said cam tracks.

2. An internal combustion engine operating on the two-stroke principle comprising a rotary member, a stationary inclosing 125 member, an annular series of parallel cylinders embodied in said rotary member, two reciprocating pistons arranged in each of said cylinders, a valve sleeve connected to one of said pistons, induction, transfer and 130

exhaust ports controlled by said sleeve, fixed cam tracks on said stationary member adapted to accommodate the action of the pistons in effecting the rotation of the rotary member comprising oppositely inclined contact edges or surfaces disposed outward of the opposite ends of the cylinders, bearing devices on the rods of the pistons for engaging said cam tracks, a shaft to which the rotary member is connected and bearings carried in the stationary member for said shaft.

3. An internal combustion engine operating on the two-stroke principle comprising a rotary member consisting of a casting, an annular series of parallel cylinders formed from open-ended tubes secured in said casting, gland plates for closing the ends of said cylinders, two reciprocating pistons arranged in each of said cylinders, glands in said gland plates through which the rods of said pistons work, a valve sleeve connected to one of said pistons, induction, transfer and exhaust ports adapted to be controlled by said sleeve, fixed cam tracks adapted to accommodate the action of the pistons in effecting the rotation of the rotary member comprising oppositely inclined contact edges or surfaces disposed outward of the opposite ends of the cylinders and bearing devices on the rods of the pistons for engaging said cam tracks.

4. An internal combustion engine operating on the two-stroke principle comprising a rotary member consisting of a casting, an annular series of parallel cylinders formed from open-ended tubes secured in said casting, gland plates for closing the ends of said cylinders, two reciprocating pistons arranged in each of said cylinders, glands in said gland plates through which the rods of said pistons work, a valve sleeve pertaining to one of said pistons which sockets over the other piston, the space within the valve sleeve and between the pistons constituting the combustion chamber of the cylinder, induction transfer and exhaust ports opened and closed by said sleeve, fixed cam tracks adapted to accommodate the action of the pistons in effecting the rotation of the rotary member comprising oppositely inclined contact edges or surfaces disposed outward of the opposite ends of the cylinders and bearing devices on the rods of the pistons for engaging said cam tracks.

5. An internal combustion engine operating on the two-stroke principle comprising a rotary member consisting of a casting, an annular series of parallel cylinders formed from open-ended tubes secured in said casting, gland plates for closing the ends of said cylinders, induction, transfer and exhaust

passages in said casting, induction, transfer and exhaust ports in said cylinder tubes, two reciprocating pistons arranged in each of said cylinders, glands in said gland plates through which the rods of said pistons work, a valve sleeve pertaining to one of said pistons which sockets over the other piston, the space within the valve sleeve and between the two pistons constituting the combustion chamber of the cylinder, ports in said sleeve for opening and closing said induction, transfer and exhaust ports in the cylinder, fixed cam tracks adapted to accommodate the action of the pistons in effecting the rotation of the rotary member comprising oppositely inclined contact edges or surfaces disposed outward of the opposite ends of the cylinders and bearing devices on the rods of the pistons for engaging said cam tracks.

6. An internal combustion engine operating on the two stroke principle comprising a rotary member, a stationary inclosing member, an annular series of twelve parallel cylinders embodied in said rotary member, two reciprocating pistons arranged in each of said cylinders, a valve sleeve connected to one of said pistons, induction, transfer and exhaust ports controlled by said sleeve, a shaft to which the said rotary unit is connected and bearings for said shaft carried in the said stationary inclosing member, cam tracks on said stationary inclosing member adapted to accommodate the action of the pistons in effecting the rotation of the rotary member, each track consisting of a horizontally zig-zagged ring concentrically disposed in relation to the said shaft and formed of four inclined planes alternately directed outwardly from and inwardly toward the said rotary member, bearing devices on all the rods of the pistons pertaining to each corresponding end of the said rotary member adapted to engage and maintain constant contact with said cam track so that the two series of piston rods and the two opposing tracks cause the pistons of each cylinder to make two working or impulse strokes and two induction and compression strokes during each complete revolution of the said rotary cylinder unit, the simultaneous firing of two diametrically opposed cylinders resulting.

In testimony whereof we have hereunto set our hands in presence of two subscribing witnesses.
